ELECTRICAL REMOTE CONTROL DEVICE

Bryan W. Chapin, Kenmore, N. Y., assignor to
Sprlesch Tool and Manufacturing Company,
Inc., Buffalo, N. Y.

Application October 27, 1943, Serial No. 567,779

5 Claims. (Cl. 172—239)

This invention relates to electric control devices or apparatus by means of which electric power may be transmitted to remote power devices for controlling their operation.

One of the objects of this invention is to provide an electric remote control device of improved construction, by means of which an electrical apparatus may be actuated at a distance to turn through any desired number of revolutions and through fractions of revolutions in synchronism with a rotatable transmitting member. Another object is to provide a device of this kind in which the accuracy of the device is greatly increased by means of gearing.

It is also an object of this invention to provide an apparatus of this kind, by means of which any desired amount of power may be provided in the receiving unit of the remote control device for doing work in accordance with the manipulation of a power transmitting device.

It is also an object of this invention to provide apparatus of this type with means of improved construction for varying the amount of current supplied to the receiving unit during the operation of the apparatus. A further object is to provide an apparatus of this kind by means of which the power delivered to the receiving apparatus is increased when the receiving apparatus is subjected to rapid rotation. Other objects of this invention will appear from the following description and claims.

In the accompanying drawings:

Fig. 1 is a face view of an electric remote control device embodying this invention.

Fig. 2 is a fragmentary sectional elevation thereof, on line 2—2, Fig. 1, and reversed end for end.

Figs. 3, 4 and 5 are respectively sectional views thereof, on line 3—3, 4—4 and 5—5 of Fig. 2.

Fig. 6 is a sectional view approximately on line 6—6, Fig. 1.

Fig. 7 is a transverse section thereof, on line 7—7, Fig. 6.

Fig. 8 is a diagram of the electrical connections.

In the particular embodiment of this invention shown by way of example in the drawings, 10 represents the housing of a transmitting or controlling apparatus or device which includes a rotatable shaft 11, and which as shown in Fig. 1, may have a suitable gear 12 mounted thereon, which in turn may be driven by a larger gear 13 secured on a shaft 14. This transmitting device is connected by means of a cable 15 including a plurality of wires insulated from each other, to a receiving or power apparatus having a hous-

ing 16 and a revolvable shaft 17 which preferably also has a gear 18 thereon driving a larger gear 19 mounted on the shaft 20. The transmitting device may be easily turned for directing current to various of the conductors in the cable 15 and this current operates a motor which may be of any suitable or desired size in the housing 16 for delivering the desired amount of power to the shaft 17.

10 The transmitting instrument or device preferably includes a series of contacts arranged in a circle. In the construction illustrated, I employ a commutator including a plurality of contacts or segments 24, and a plurality of brushes 25 which contact therewith, see particularly Figs. 2 and 5. The brushes and commutator are rotatable relatively to each other to enable the brushes to contact with different segments of the commutator. In the particular construction shown, 20 the commutator is stationarily mounted on an end plate 23 suitably secured to the housing 10 of the transmitting device, and the brushes 25 are mounted in a revolving disk or frame member 27 which may be rigidly mounted on the shaft 11, or as hereinafter described, this member 27 may be rotatably mounted on the shaft and may be rotated from a bushing 28 secured to the shaft 11. This disk or frame member 27 may, for example, be made of insulating material having 25 the brushes 25 mounted in cylindrical guide sleeves or cups 29 having springs 30 therein which press the brushes against the commutator segments 24. Four brushes are shown in the construction illustrated, but two brushes may be provided or more than four brushes, as may be desired. Brushes or contact devices of any other suitable form may be provided, if desired. Current may be supplied to the revolvable brushes in any suitable manner, for example, by means 30 of a slip ring, which may be mounted on a disk 33 which in turn is suitably mounted on the insulating frame member 27 which carries the brushes. For example, the member 27 may have an extension 32 of semi-cylindrical form to which the disk 33 may be secured, for example, by means of screws as shown in Figs. 2 and 4. The disk 33 may have a slip ring 35 mounted thereon and suitably insulated therefrom and connected with one set of brushes 29 by any suitable conductor 35 not shown in Fig. 2, but indicated in the wiring diagram in Fig. 8. The other set of brushes may be connected directly to the disk 33 which may have an annular surface 36 formed thereon, thus producing a collector ring integral with the disk. Electric current may be transmitted to the col-

lector rings 35 and 36 in any suitable manner, for example, by means of brushes 37 and 38, suitably mounted on and insulated from an end wall 39 of the housing 10.

From the foregoing description, it will be obvious that if the shaft 11 is rotated, the brushes 29 of the frame member 27 will contact with different segments 24 of the commutator and current will pass through these segments and through the conductors connected therewith which extend in the form of a cable 15 into the receiver housing 16.

The receiver as clearly shown in Figs. 6 to 8 may be in the form of a motor having a stationary armature and revolving fields, the armature including a core 42 wound with a series of coils connected with the conductors in the cable 15. The armature core 42 of this motor is, as usual, provided with a series of longitudinal slots 43 therein to receive the armature coils 44. These coils may be wound in any suitable or desired manner, and as indicated in Fig. 8, each coil spans one slot 43. Each coil has a tap leading to one of the conductors of the cable 15 as clearly shown diagrammatically in Fig. 8. Consequently, as the brushes in Fig. 8 move about the commutator, current will be conducted to different coils of the armature through the cable 15, thus producing a revolving magnetic field.

The pole pieces of the motor are mounted on the shaft of the motor and revolve within the armature, the pole pieces including any usual or suitable iron cores 47 having field coils 48 around them to which electric current may be conducted from any suitable source of power through collector rings 50 and 51 which, in the construction illustrated, are mounted on the opposite ends of the core 47 of the rotating field, and these collector rings may be connected to the field coils 48 in any suitable manner. Current may be conducted to the collector rings 50 and 51 by means of brushes 52 and 53 mounted on and insulated from the end walls 54 and 55 in the motor housing. Obviously as the magnetism in the armature moves about the axis of the shaft 17, if the field is excited, the shaft 17 will be revolved or turned to the same extent as the brushes 29 of the transmitter apparatus. By having the brushes 52 and 53 bear against opposite sides of the revolving pole pieces, the end thrust of one brush will be counteracted by the end thrust of the other brush.

By inspection of the diagram as shown in Fig. 8, it will be clear that the revolving field will be moved into many more different positions about the axis of the shaft 17 than the number of segments on the commutator, this being due to the fact that the brushes may at times contact more than one segment. By making the brushes of somewhat larger cross sectional area than shown in the drawings, so that each brush will always contact at least two segments of the commutator, a still higher degree of accuracy may be obtained, if desired. The motor may be built of any suitable or desired size so that practically any desired amount of power may be developed at the receiving end.

In the use of the apparatus thus far described, it will be obvious that the brushes of the commutator may be turned in either direction, since the rotary field will follow the field set up by the armature winding in either direction, at any desired speed, providing that the brush acceleration does not exceed the acceleration of the field for a set voltage and ampere load rating. Con-

sequently, the pole pieces will rotate synchronously within the speed range of the apparatus and the rotatable field will also assume angular positions approximating very closely the angular positions of the brushes relatively to the commutator.

Since the number of segments in the commutator and the number of slots of the armature are necessarily limited, there will of necessity be small angles of movement of the brushes which will not result in corresponding movements of the motor shaft 17. This error can, however, be reduced to any desired extent by means of the gearing connected with the shafts 11 and 17. For example, if the ratio of the gears 13 and 18 to the gears 12 and 16 is ten to one, then the error in movement of the shaft 14 relatively to shaft 20 will be reduced to approximately one-tenth of that between the shafts 11 and 17.

It is, of course, desirable at times to rotate the brushes very slowly or to leave the brushes in a fixed position for a considerable period of time, and since it takes very much less power to hold the pole pieces and shaft 17 in fixed position than to rotate them, I have provided means for varying the current supplied to the armature by the rotating brushes, and in the construction illustrated by way of example, this may be accomplished by means which may be mounted on the disk or frame 27 and on the hub 28 of the shaft 11 of the transmitter, and which are shown in Figs. 2, 4 and 8. When such means are employed, the brush carrying frame or disk 27 is preferably mounted to have at least limited movement about the shaft 11 and rotary motion of the shaft is transmitted to this disk or frame by means of a rod or arm 60 secured to and extending outwardly from the hub 28. The arm 60 is made of conducting material and is insulated from the shaft 11 and for this purpose, the hub or sleeve 28 is preferably made of insulating material having the arm 60 molded or otherwise suitably secured thereto. This arm is arranged with its outer end between two contacts 61 and 62 which are suitably secured on the disk or frame 27. Consequently, when the shaft 11 is rotated in one direction, the arm 60 will move into engagement with one of the contacts and will impart rotary motion to the brush carrying disk 27. When the shaft 11 is turned in the opposite direction, the arm engages the other contact and moves the disk 27 in the opposite direction, the arm preferably having contacts engaging the contacts 61 and 62.

Suitable means are provided for normally holding the arm 60 out of engagement with both of the contacts 61 and 62 and by way of example, I have shown in Fig. 4 a pair of springs 63 and 64 which are suitably mounted on the disk 27 and engage opposite sides of the arm 60 so as to hold the same in the position shown in Fig. 4, in which it engages either of the two contacts 61 and 62. 65 represents a resistance which may be mounted on the disk 27 or otherwise, and which is normally connected in the circuit leading to one set of brushes 28. When the arm 60 engages either of the contacts 61 and 62, the resistance 65 is short-circuited. Consequently, when sufficient torque is applied to the shaft 11 to overcome the resistance of the springs, the arm 60 short-circuits the resistance 65 so that an ample supply of current will pass to the receiver motor to effect rotation of the same. When no torque or only a slight torque is applied to the shaft 11, the springs 63 and 64 will move the arm 60 into neutral or

midway position between the two contacts 61 and 62 so that the resistance 65 again is in the circuit, thus reducing the current supplied to certain coils of the motor and avoiding overheating of the same.

The springs 63 and 64 are preferably of such strength that they will return the arm 60 to neutral position out of engagement with the contacts 61 and 62 unless the disk 27 is being accelerated or decelerated. If the shaft 11 should be rotated at a uniform speed for a period of time, the arm 60 may, consequently, move out of engagement with its contacts, thus reducing the current supplied to the motor. However, since the motor might require considerable current while being rotated in this manner, I preferably provide means for short-circuiting the resistance 65 when the shaft 11 attains a certain speed. In the construction shown by way of example, I provide on the insulating disk 27 a contact 70 and I also provide another contact 71 on one end of a spring 72, the other end of which may be secured to the disk 27. The free end of the spring may also be provided with a small weight 73 so that when the shaft 11 is rotating, the spring will be moved by centrifugal force so that its contact 71 will engage the contact 70 on the disk 27 to short-circuit the resistance 65.

Fig. 8 shows the electrical connections between the various parts of the apparatus which have been described, and in this figure, L' and L² represent two power supply lines. In the particular diagram shown, the field coils of the motor are connected in series with the armature, and consequently, conductor 80 connects the line L² with one terminal of the field winding through one of the brushes 52 or 53 and the other brush connects with conductor 81 which extends to the brush 38 contacting with collector ring 35. The other line L' is connected to the other brush 37 contacting with the collector ring 33. It will be understood that the field coils of the receiver motor may be connected either in series or in parallel with the armature. In the diagram, the current to the field coils as well as to the armature is varied by including the resistance 65 in the circuit or by short-circuiting this resistance, but the field current and the armature current may, if desired, be controlled separately or jointly by any other suitable means, and if desired, the current for exciting the field may be obtained from a different source of power than that supplying the commutator and armature.

Current from the brush 38 passes through the collector ring 35 and by means of conductors 75 to one pair of brushes 25 which act on the commutator segments 24. A conductor 76 carries current from the disk 33 to one end of the resistance 65 and also to the arm 60 and to the contact member 70. The other end of the resistance 65 is connected by means of conductor 77 to the other two brushes 25, the conductor 77 also being connected with the terminals 61 and 62. Each of the segments 24 of the commutator is connected by a single conductor forming a part of the cable 15 to a connection or terminal between adjacent armature coils 44.

From this wiring diagram, it will be obvious that when torque is supplied in either direction to the shaft 11 to rotate the brushes 25 relatively to the commutator segments 24, the arm 60 will engage either contact 61 or 62, and in that case, the resistance 65 will be short-circuited until torque is no longer applied to the shaft 11, whereupon the arm 60 will assume a position inter-

mediate of the two contacts 61 and 62, so that further current passing through the brushes will also have to pass through the resistance 65. When the shaft 11 has been brought up to the desired speed of rotation so that no further acceleration takes place, the arm 60 will again assume its position out of engagement with the contacts 61 and 62 which would tend to cause the current to flow through the resistance 65 but if the speed of the shaft 11 is sufficient, the contacts 71 and 70 will engage, thus again short-circuiting the resistance 65 so that an ample supply to the commutator and motor will be ensured, thus preventing the motor from getting out of phase with the commutator.

While I have shown in Fig. 8, the conductors in the cable 15 connecting the armature coils and commutator segments in such order that the armature rotates in the same direction as the brushes, it will be obvious that the connections may be made in reverse order, so that clockwise rotation of the brushes on the commutator will result in counterclockwise rotation of the pole pieces. The apparatus will operate either on direct or alternating current.

The rotating field will follow the brushes for fractions of revolutions, but when the brushes are moved through a small angle, the rotating poles will not always move through the same angle. This difference in angle may, however, be greatly reduced by means of gearing or the like. For example, in the construction illustrated, small angular adjustments of the shaft 14 will result in very nearly the same angular movements of the shaft 20.

By means of my construction, it is, of course, possible to provide two or more receiver motors connected for operation by a single transmitter. These motors are preferably similar and will, consequently, have the same lag characteristics with reference to the transmitter, and consequently, if for example one motor operates a gun and the other a sight, the gun and sight will at all times be operated in exact synchronism with each other.

I claim as my invention:

1. A transmitter for a remote control device comprising a commutator having a plurality of segments, brushes connected with a source of current supply and contacting said commutator, said commutator and said brushes being rotatable relatively to each other to cause said brushes to contact with different segments of said commutator, and means operated by torque applied to produce relative rotation of said commutator and brushes for supplying an increased current to said motor during application of said torque.

2. A transmitter for a remote control device comprising a commutator having a plurality of segments, brushes connected with a source of current supply and contacting said commutator, said commutator and said brushes being rotatable relatively to each other to cause said brushes to contact with different segments of said commutator, a resistance controlling the current supplied to said commutator, and means actuated by torque applied to produce relative movement of said commutator and brushes for short-circuiting said resistance.

3. A transmitter for a remote control device including a commutator and brushes and means including a current carrying arm for producing relative movements of said commutator and brushes, contacts engaged by said arm when moved in either direction for producing said

movements, and resilient means for normally holding said arm out of engagement with said contacts, a circuit for carrying current to said brushes and commutator and including a resistance and connected to said arm and said contacts whereby engagement by said arm of said contacts short-circuits said resistance.

4. A transmitter for a remote control device comprising a commutator and brushes and means for producing relative motion of said commutator and brushes, a resistance for reducing the amount of current supplied to said commutator, said means having mounted thereon a part re-

sponsive to centrifugal force for short-circuiting said resistance when said means are rotated in excess of a predetermined speed.

5. A transmitter for a remote control device comprising a commutator and brushes and means for producing relative motion of said commutator and brushes, a resistance for reducing the amount of current supplied to said commutator, and connections for short-circuiting said resistance in response to torque applied to said motion producing means.

BRYAN W. CHAPIN.
